United States Patent Office

Des. 186,341
Patented Oct. 13, 1959

186,341

SURFBOARD

Frank C. Rueff, Austin, Tex.

Application March 10, 1959, Serial No. 54,921

Term of patent 14 years

(Cl. D71—1)

Fig. 1 is a side view in perspective showing the top deck of the surfboard and a portion of the port side;

Fig. 2 is a top plan view of the surfboard of Figure 1;

Fig. 3 is a side view of the surfboard in elevation;

Fig. 4 is a perspective view of the bottom of the surfboard, the near side thereof being the starboard side; and

Fig. 5 is a bottom plan view of the surfboard.

I claim:

The ornamental design for a surfboard, substantially as shown.
